UNITED STATES PATENT OFFICE.

THOMAS A. HUTSELL, OF SPOKANE, WASHINGTON, ASSIGNOR TO HUTSELL MOTOR COMPANY, OF SPOKANE, WASHINGTON.

PISTON.

Application filed December 21, 1925. Serial No. 76,647.

My present invention relates to improvements in pistons for use in internal combustion engines. The primary object of the invention is to so construct the head of the piston in such manner that the fresh fuel charge and gases of combustion in the engine cylinder will be controlled whereby economical and efficient operation of the engine is assured, a maximum mixing and compression of the fuel charge in the cylinder is secured, with a maximum development of power.

By the construction and arrangement of the head or upper portion of the piston according to my invention means are provided whereby the fresh fuel charge is introduced to the cylinder with a swirling motion or current and the current is guided and directed into the cylinder over the top of the piston head for the mixture of the fuel charge and for the purpose of assisting in the discharge of the gases of combustion from the cylinder.

While my invention is applicable for use with various forms of pistons for internal combustion engines, for purposes of illustration I have shown it as embodied in the tandem form of piston. These pistons are used in a pair of parallel engine cylinders having pump and working cylinders corresponding to the pump and working portions of the tandem pistons. In the engine a tubular passage is used to connect the interiors of adjacent working cylinders and one pump cylinder and piston are used to transfer a fresh fuel charge to an adjacent working cylinder.

The invention consists in certain novel features of construction and combinations and arrangements of parts involving the head of the working or power piston as will hereinafter be more fully pointed out and claimed.

In the accompanying drawings I have illustrated one complete example of the physical embodiment of my invention wherein the parts are combined and arranged in accordance with one form for the practical application of the principles of my invention.

Figure 1 is a view in elevation of a tandem piston having the features of my invention embodied therein.

Figure 2 is a perspective view of the head

of the working or power piston involving my invention.

Figure 3 is a transverse sectional view of a portion of an internal combustion engine showing the working or power cylinders and a transfer passage therebetween, together with the pair of working pistons in top plan view.

In carrying out my invention according to the structure exemplified in the drawings, Figure 3, I utilize a pair of working cylinders 1 and 2 located in parallelism, and connected by a tubular transfer passage 3 by means of which a fresh fuel charge may be transferred from one working cylinder to another working cylinder, said tubular connection being located preferably near the lower ends of these cylinders.

The tandem piston as seen in Figure 1 comprises a pump piston of large area indicated as 4 and a smaller power or working piston 5, both of which may be hollow, and the working piston has lateral ports 6 therein utilized in transferring gases from one engine to another.

The working or power piston 5 has a closed upper end or head 7 presenting a flat top surface for the piston, and this head of the piston is designed to co-operate with the transfer passage 3 for transferring gas from one cylinder to the other through the passage 3 in Figure 3. On the top of the head and projecting therefrom is fashioned an arcuate baffle plate 8, the radius of which is less than the diameter of the piston, or in other words the baffle plate is inset from the periphery of the piston.

This plate in its arcuate form extends around a portion of the piston head and one portion of the plate is fashioned with a laterally extending, angular or horizontal flange 9 which occupies the space between the inner face of the arcuate baffle plate and the annular periphery of the piston i. e. the outer edge of the flange is of the same diameter as the piston. This flange has its top face flush with the top edge of the baffle plate and at one end the flange terminates in an abrupt shoulder 10 the same width as the flange and integrally connecting the flange with the head 7.

Beneath the flange 9 is provided an arcuate groove opening at the periphery of the piston, and the base or lower face of this

horizontally extending groove merges into a spirally arranged flat face 12 extending around the exterior of the baffle plate, rising to its top free edge and terminating in an 5 obliquely extending edge, on a line with the obliquely extending edge of the shoulder 10 at the opposite end of the baffle plate.

The pistons in Figure 3 are arranged in complementary pairs with the specially 10 formed heads in opposition and arranged to cooperate at the ends of the transfer passage 3.

As seen in Figure 3 the fuel charge is being transferred from cylinder 1 to cylinder 15 2 as indicated by the arrows. When the fuel gas strikes the baffle wall 8 and the inner wall of the arcuate groove the shoulder 20 10 forms an abutment against passage of the gas directly across the head of the piston, and the gas currents are directed and guided in the groove to start an initial swirling movement around and in contact with the inner face of the cylinder wall 2, as the gases pass from under the flange 9.

The upwardly inclined or spiral face 12 causes an upward movement of the swirling currents over the top of the baffle wall. This swirling movement of the gases, in addition to performing the function as a scavenger to force out spent gases, also insures a mixture of the fresh charge as it is being compressed by the up-stroke of the working piston. When the charge is fired in the cylinder a broad and expansive flame is 35 forced over the baffle wall 8 to insure igni-

tion over the entire area of the piston head and a consequent powerful stroke of the piston. At the inner curved side 14 of the baffle plate or wall, the exhaust gases are deflected downwardly by the incoming fresh 40 charge of gas which forms an envelope over the outgoing exhaust gases to confine them and assist in their discharge.

Having thus fully described my invention, what I claim as new and desire to 45 secure by Letters Patent is—

1. A piston having a closed head and fashioned with an inset arcuate baffle plate, and an annular flange on part of said plate to and extending to the edge of the piston 50 to form an arcuate exterior groove in the side of the piston head.

2. A piston having a closed head and fashioned with an inset arcuate baffle plate, an angular flange on part of said plate forming a lateral groove, and a spiral face on said head exterior of the plate merging with the lower face of said groove.

3. A piston having a closed head and fashioned with an inset baffle plate of arcuate 60 form, an annular flange on part of said plate forming an exterior lateral groove and an abutment shoulder closing one end of said groove, said shoulder and flange extending to the periphery of the said piston, and a spiral face on said head exterior of the 65 uncovered portion of the plate for guiding swirling currents of gas.

In testimony whereof I affix my signature.
THOMAS A. HUTSELL.
